Des. 237,975
Patented Dec. 9, 1975

237,975

COMBINATION PERFORATOR AND PERFORATED TAPE READER

Gene D. Vedder, Granada Hills, Calif., assignor to
Ex-Cell-O (Remex)

Filed Sept. 7, 1973, Ser. No. 395,197

Term of patent 14 years

Int. Cl. D14—02

U.S. Cl. D26—5 C

Fig. 1

Fig. 5

FIG. 1 is a front elevational view of the combination perforator and perforated record reader showing my new design;

FIG. 2 is a top plan view thereof;

FIG. 3 is a left side elevational view thereof;

FIG. 4 is a right side elevational view thereof; and

FIG. 5 is a front perspective view thereof.

The bottom view of the combination perforator and perforated record reader is plain and unornamented.

I claim:

The ornamental design for a combination perforator and perforated tape reader, as shown and described.
